TREATMENT OF OLEFINS WITH LIQUID ANHYDROUS HYDROGEN BROMIDE

Carl B. Linn, Riverside, and Robert J. Newman, Lyons, Ill., assignors to Universal Oil Products Company, Chicago, Ill., a corporation of Delaware

No Drawing. Application July 30, 1945,
Serial No. 607,906

12 Claims. (Cl. 260—663)

1

This invention relates to the treatment of olefinic hydrocarbons with anhydrous liquid hydrogen bromide. More particularly, it relates to the production of alkyl bromides from aliphatic olefins. It is also concerned with the manufacture of alkyl aromatic hydrocarbons by the interaction of an aromatic hydrocarbon and an olefin in the presence of hydrogen bromide.

Alkyl bromides have assumed considerable importance in recent years as starting materials for the production of a great many types of organic derivatives. Consequently, the need has arisen for an inexpensive method of preparing these compounds that can be adapted readily to large scale commercial operation. The present invention comprises in part a simple process for manufacturing alkyl bromides which can be easily adapted to commercial practice and which is characterized by high yields of the desired products and low yields of undesired products. This process involves the hydrobromination of olefins with liquid hydrogen bromide in the absence of solvents.

The large demand for alkyl aromatics, such as ethyl benzene, cumene, cymene, etc. is well known. It is another feature of our invention to provide a new method of producing these valuable alkyl aromatics.

In one embodiment our invention consists of a process for producing valuable derivatives of olefinic hydrocarbons which comprises treating said olefins with anhydrous liquid hydrogen bromide. In a more specific embodiment the present invention relates to a process for producing valuable derivatives of olefinic hydrocarbons which comprises treating said olefins with anhydrous liquid hydrogen bromide in the presence of an aromatic hydrocarbon.

Olefins which may be treated in accordance with the present invention may be either normally gaseous or normally liquid and comprise ethylene, propylene, butylenes, amylenes, hexylenes and their higher homologues, including various polymers of normally gaseous olefins. These olefins may be obtained from any source and include products of catalytic and thermal cracking of oils and those obtained by dehydrogenating the corresponding paraffinic hydrocarbons or by dehydrating alcohols.

Aromatic hydrocarbons such as benzene, toluene, other alkylated benzenes, naphthalene, alkylated naphthalenes, other poly-nuclear aromatics, etc., which are alkylated by olefinic hydrocarbons as hereinafter set forth may be obtained by the fractional distillation of petroleum, by the

2

destructive distillation of coal, by the dehydrogenation and cyclization of aliphatic hydrocarbons and of alkylated aromatic hydrocarbons, and by other means.

5 The present process may be carried out in batch or continuous type operation. In the batch operation of this process anhydrous liquid hydrogen bromide is agitated within a mixer and the olefin is gradually introduced below the surface of the acid. After the olefin has been contacted with the hydrogen bromide for suitable length of time, the agitation may be stopped and the hydrocarbons separated and fractionated to recover the desired products. In the continuous type of operation, the hydrocarbon charge stock is fed to contactors in which intimate contact between the hydrocarbon and acid is maintained. The effluent from the contactors is treated for the separation of the acid from the hydrocarbon, the acid being returned to the contactors and the hydrocarbon being fed to the fractionation system. The hydrocarbon stream leaving the separator contains a small amount of dissolved hydrogen bromide, which may be removed by treatment with caustic, by fractionation, or by other suitable means. Hydrocarbons of high molecular weight and low hydrogen content gradually accumulate in the catalyst and should be removed by distillation or other suitable means in order to maintain the activity of the acid at the desired level.

25 The exact temperatures and pressures which should be employed will depend upon the activity and physical characteristics of the hydrocarbons involved. As a rule, excessive elevated temperatures are not necessary and good results are obtained below 200° C. Only sufficient pressure need be used to maintain the reactants in the liquid phase. Contact times of from about 1 to about 60 minutes are preferable.

35 The following examples are given to illustrate the character of the results obtained by the use of the present process, although the examples given are not introduced with the intention of unduly restricting the generally broad scope of the invention.

40 In Examples 1 and 2, the reactions were carried out in a steel turbomixer by charging a weighted amount of anhydrous liquid hydrogen bromide to the mixer and gradually adding the hydrocarbons while maintaining vigorous agitation. At the conclusion of the tests, the acid and hydrocarbons were separated and the latter was scrubbed with caustic, dried, and analyzed. In Examples 3 and 4, the reactions were carried 45 out in a steel rotating autoclave. The anhydrous

liquid hydrogen bromide was first added to the autoclave and then the hydrocarbon was added. Following the period of contacting, the contents were removed and the hydrocarbon product was caustic washed, dried, and analyzed. The operating conditions and results of these runs are summarized in the following table.

Example No.	1	2	3	4	10
Apparatus	Turbomixer		Rotating Autoclave		
Temperature, °C.	10	10	20	150	
Time, Hours	3.0	4.25	8	4	
Pressure, P. s. i.:					
Initial	165	150	360	400	
Final	100	10	200	375	
Charge, Grams:					
HBr	227	191	147	137	
Isobutane	295	0	0	0	
Normal Butane	90	0	0	0	
Benzene	0	441	88	88	
Propylene	0	88	0	0	
Ethylene	0	0	22	26	
Recovery, Grams:					
Isobutane	300				
Sec. Butyl Bromide	189				
Higher Boiling Point Material	11				
Benzene	416				
Isopropyl Bromide	101				
Cumene	9				
Higher Boiling Point Material	4				
Benzene	80.0		59.8		
Unreacted Ethylene	7.0		2.0		
Ethyl Bromide	35.2		39.4		
Ethylbenzene	8.8		18.8		
Diethylbenzene	2.3		10.5		
Higher Boiling Point Material			6.5		

¹ Maximum.

In Example 1, 86 mol percent of the butene charged was actually recovered as secondary butyl bromide in spite of inevitable losses. The higher boiling material contained bound bromide. It will be noted that this experiment was carried out in the presence of isobutane, which acted as a diluent. In Example 2, 74% of the propylene was converted to isopropyl bromide and 3.6% of the propylene charged was recovered as cumene. At room temperature, as shown in Example 3, 32% of the ethylene charged did not react. Of that which did react, 60% went to ethyl bromide and 16% to ethylbenzene. The experiment was repeated by adding the reactants and catalyst to the autoclave at room temperature and heating to 150° C. in Example 4. Under these conditions only 8% of the ethylene did not react. Of that which did react, 42% went to ethyl bromide, 21% to ethylbenzene, and 18% to diethylbenzene.

The results of these experiments show that olefins can be converted into alkyl bromides in excellent yields by treatment of said olefins with liquid hydrogen bromide. This is true for pure olefins as well as for mixtures of olefins with other hydrocarbons. The results also show that aromatic hydrocarbons can be alkylated with olefins in the presence of liquid hydrogen bromide.

In one modification of our invention, mixtures of olefins and other hydrocarbons, particularly mixtures of olefins and paraffins, can be separated readily without the side reactions which characterize most chemical methods of separation. As illustrated in Example 1, a narrow boiling mixture of paraffins and olefins are contacted with liquid hydrogen bromide and the olefins are thereby converted to alkyl bromides. The hydrocarbons are separated from the acid and the bromides are recovered by fractionation or other suitable means.

We claim as our invention:

1. A process for producing valuable derivatives

of olefinic hydrocarbons which comprises treating said olefins with a halide material consisting essentially of anhydrous liquid hydrogen bromide.

5. A process for producing alkyl bromides which comprises reacting an olefin with anhydrous liquid hydrogen bromide.

3. A process for producing alkyl bromides which comprises reacting a normally gaseous olefin with anhydrous liquid hydrogen bromide.

4. A process for producing alkyl bromides which comprises reacting a normally liquid olefin with anhydrous liquid hydrogen bromide.

15. A process for the manufacture of ethyl bromide which comprises reacting ethylene with anhydrous liquid hydrogen bromide.

6. A process for the manufacture of propyl bromide which comprises reacting propylene with anhydrous liquid hydrogen bromide.

20. A process for the manufacture of butyl bromide which comprises reacting butylene with anhydrous liquid hydrogen bromide.

8. A process for producing alkylated aromatic hydrocarbons which comprises contacting an aromatic hydrocarbon with an olefinic hydrocarbon under alkylating conditions in the presence of a halide catalyst consisting essentially of anhydrous liquid hydrogen bromide.

25. A process for producing ethylated benzene which comprises subjecting benzene to contact with ethylene under alkylating conditions in the presence of a halide catalyst consisting essentially of anhydrous liquid hydrogen bromide.

30. A process for producing propylated benzene which comprises subjecting benzene to contact with propylene under alkylating conditions in the presence of a halide catalyst consisting essentially of anhydrous liquid hydrogen bromide.

40. A process for the separation of olefins from hydrocarbon mixtures containing olefins which comprises treating said mixtures with anhydrous liquid hydrogen bromide, separating the hydrocarbon product from the acid layer, and recovering the alkyl bromides from said hydrocarbon product.

45. A process for producing an alkyl bromide and an alkylated aromatic hydrocarbon which comprises subjecting a mixture of an olefin, an aromatic hydrocarbon and a halide catalyst consisting essentially of anhydrous hydrogen bromide to reaction at an alkylating temperature and under sufficient pressure to maintain the hydrogen bromide in liquid phase.
